UNITED STATES PATENT OFFICE.

JAMES HARPER PHELPS, OF SHARON, WISCONSIN.

TYPE-WRITER.

SPECIFICATION forming part of Letters Patent No. 656,658, dated August 28, 1900.

Application filed December 23, 1899. Serial No. 741,375. (No model.)

To all whom it may concern:

Be it known that I, JAMES HARPER PHELPS, a citizen of the United States, residing in Sharon, in the county of Walworth and State 5 of Wisconsin, have invented a new and useful Improvement in Type-Writers, of which the following is a specification.

In ordinary type-writing practice it often occurs that the operator wishes to move the 10 paper-carriage back to the right one or two or more spaces in order to make a correction or to restrike a character which had made a faint impression, and in all such cases it is usually an awkward operation to reach one 15 or both hands up to the carriage and draw it carefully to the right the number of spaces desired, the awkwardness of the operation being increased because of the amount of lost motion in the working parts of the machine, 20 which makes it necessary to move the carriage almost two spaces in order to attain one or to move it nearly three spaces to secure two, and it often occurs that even with ordinary care the carriage is not returned to the 25 exact position desired. By the use of my invention, which has for its object the imparting to the carriage of a step-by-step backward movement, the carriage may be quickly returned short distances whatever may be 30 its position at the time and with far greater precision and convenience than has been possible heretofore. To accomplish this result, I combine with the paper-carriage of the type-writer means for imparting to the carriage a step-by-step movement from left to 35 right and a key or keys or other suitable devices for actuating said means at will. In the preferred form of the invention I employ two keys, one moving the carriage a single 40 letter-space at each impulse and called the "reverse-key" and the other moving it two letter-spaces at each impulse and called the "double-reverse key." By operating these 45 keys or either of them repeatedly the carriage may be moved back any distance desired.

The nature of the invention, as well as the details thereof, is fully set forth below in the description forming a part of this specification and also illustrated in the accompanying drawings, in which--

Figure 1 is a plan of a type-writer provided with my invention. Fig. 2 is a partial side elevation. Fig. 3 is a vertical section in a plane extending from front to rear. Figs. 55 4, 5, and 6 are detail views showing the rack and pawl whereby the carriage is moved back in different positions. Fig. 7 is a sectional view showing the mechanism connecting the pawl with the keys. Fig. 8 is a section on the lines 8 8 of Figs. 5 and 7. Fig. 9 is a detail elevation of the reversing-keys, and Fig. 10 is a section on the line 10 10 of Fig. 9.

In said drawings, A represents the frame 65 of the type-writer; B, the ordinary character-keys; C, the paper-carriage frame, sliding on ways C', and D the platen-roller. The carriage is provided with the usual rack-plate E, engaged alternately by dogs F and F', usually employed to limit the feeding impulses given the carriage by the character and spacing keys, such dogs being supported on the swinging end of a lever F², which is depressed by the keys through the medium of the adjustable connection F³, attached to the rocking frame F⁴, pivoted at F⁵ and engaged by all the key-levers, as shown at F⁶. These 70 parts are all of the ordinary construction. 75

Attached to the machine are operating devices whereby the operator may reverse the movement of the paper-carriage. As already stated, I prefer to employ at least two of these devices, one acting to return the carriage two spaces and the other a single space, and I also 80 prefer to make these devices in the form of keys, G being the single-space key and H the double-space one; but obviously the two-space key or device may be dispensed with and the same result be obtained by repeating 85 the strokes of the one-space key or device. These keys G and H are desirably located at the right side of the machine, as shown; but they may be located elsewhere, if preferred. A desirable construction of these keys is that 90 shown, the key H being integral with the lever H', pivoted at H², and the key G being carried by lever H' and being provided with a short lever G', pivoted at G² to lever H' and resting at its outer end on a stud G³, inserted 95 in said lever. Both levers are guided by the slotted guide H³, attached to frame A and 100

having a shoulder G^3 , limiting the stroke of key G , while the key H remains at liberty to move down until it strikes the horizontal part H^4 of the guide. With this construction key 5 H is adapted to impart a full stroke to lever H' , and thereby cause the actuation of the carriage for two character-spaces, while the key G will be arrested by the shoulder G^3 , and thus be enabled to impart only a half-stroke 10 to said lever, and thereby move the carriage a single space only. Key G is adapted to carry the lever H' with it the distance permitted by said shoulder G^3 , and it does not interfere with the long strokes of key H by 15 reason of its pivoted attachment to the lever H' . The dotted lines in Fig. 9 show the different positions of the two keys and their levers. The connections between these keys and the carriage may be of any suitable construction; but the construction shown and now to be described is the best now known to me. Attached to key-lever H' is a rod J , having its upper end pivotally joined to an elbow-lever J' , pivoted at J^2 and actuating a 20 horizontal bar J^3 , attached to its upper end. To the farther end of bar J^3 is pivoted a pawl 25 K , engaging a rack on the carriage, preferably the rack of plate E . A right-angle frame $J^4 J^5$, stationarily supported from the main 30 frame and having its ends slotted, as shown in the case of the member J^4 , supports and guides the acting end of the pawl and also supports and guides in like manner the arm J^6 , projecting at right angles from the base 35 of the pawl. This arm is integral or otherwise made rigid with the pawl, so that the spring J^7 , which is attached to the arm J^6 and to the frame member J^5 , may when distended by the backward movement of the pawl cause 40 the pawl to move into engagement with the rack. This backward movement of the pawl takes place whenever either of the keys G or H is depressed, the movement of lever H' causing a rocking of lever J' , which pulls the pawl 45 in the direction which distends spring J^7 and brings about engagement with the rack. The pawl as soon as it enters the rack compels it and the carriage to move back to the extent of a single space or two spaces, according to 50 the extent of the stroke given to key-lever H' . When the operator releases the reversing-key, the spring L raises it and lever H' , thereby rocking lever J' back to its original 55 position and pushing the pawl forward to its normal position, such forward movement causing disengagement of the pawl and rack because of the inclination of the rack-teeth. Fig. 4 shows the pawl in its normal position, Fig. 5 shows it as having just engaged the 60 rack, and Fig. 6 shows it as having retracted the rack.

Of course it will be understood that a stop-motion device will be employed with the reversing mechanism to retain the carriage in 65 any position to which it may be moved by my reverse mechanism; but the dog F' found in the ordinary construction of type-writers

may be employed for this purpose, as it is yielding, so that it moves out of the rack readily and offers no resistance to movement 70 in the direction in which the carriage is actuated by my invention, but quickly enters the rack and locks it against movement in the other direction.

The top of frame member J^4 is slotted, as 75 at J^{10} , and the arm J^6 is provided with a pin J^{11} , working in said slot and preventing the arm from slipping out of the frame. Lifting-springs L^1 and L^2 are employed to raise the 80 frame F^4 and the character-key levers after their actuations.

When composing on a visible-writing machine—such as Oliver, Willians, Blickensderfer, or Wellington—the reverse-keys will also be found very useful in recording arithmetical operations, especially those involving addition or subtraction, as the numbers to be added or subtracted can be tabulated on the machine and the answers written down as obtained, commencing at the right and 90 writing toward the left, as would be the case when writing them with a pen or pencil, thus:

From 874509
take 738422

95

136087

In the above computation after the figures are written down ready for subtraction the operator first takes "2" from "9" and writes 100 the result, "7," beneath in proper position. Then he strikes the double-reverse key, which brings the carriage in proper position to write the next figure, "8." He then strikes the double-reverse key again and writes the "0," 105 after which he strikes the double-reverse key again and brings the carriage in proper position to write the "6," and so on till the answer is all written, the figures having been written down from right to left. In addition 110 the same method may be employed with like results, thus:

Add 456843
864901
268493

119

1590237

In this operation we first add the right-hand column and write down the "7," then strike 120 the double-reverse key, add the next column, and write the "3," then strike the double-reverse key again and then write the "2," and so on till all the figures in the result have been written.

The invention is shown as being applied to a Densmore or similar type of machine; but it will be understood that it can be applied to any machine having a traveling paper-carriage. It will also be understood that a special rack may be attached to the carriage instead of utilizing the rack E customarily used on such carriages and that the teeth of the rack need not point horizontally backward,

125

130

as in the machine illustrated. Neither need the customary stop device F' be used, but a special stop may be provided in its stead.

I claim—

- 5 1. The combination with the paper-carriage of a type-writer, of means for imparting a step-by-step movement from left to right to the carriage, a key or lever for causing single-space movements and a key for causing double-space movements by the carriage, substantially as specified.
- 10 2. The combination with the paper-carriage and its locking rack and dog, of a pawl engaging said rack and having an arm extending at right angles from its base, a stationary support for said pawl, a movable bar to which the pawl is pivoted, means for actuating said bar, and a spring attached to said arm and support and acting to throw the pawl against the rack, substantially as specified.
- 15 3. The combination with a type-writer of two reverse-keys, and mechanism connecting them to the paper-carriage, one of said keys acting to cause a backward movement by the carriage equal to a single character-space, and the other acting to cause a similar movement equal to two character-spaces, substantially as specified.
- 20 4. The combination with a reverse-key and the paper-carriage, of a pawl engaging the carriage-rack and having an arm extending at right angles from its base, a supporting-frame J⁴ J⁶, having a slot J¹⁰, a projection J¹¹ on the pawl-arm, means for actuating the pawl and a spring acting to throw the pawl into engagement, substantially as specified.
- 25 5. The combination with the paper-carriage and mechanism for reversing it, of two keys, one for moving the carriage a single space and the other for moving it two spaces, the two-space key being connected to said mechanism and the one-space key being pivoted upon the two-space key and imparting a partial stroke to the latter, substantially as specified.
- 30 6. The combination with the paper-carriage and the mechanism for reversing it, of two keys for imparting one-space and two-space reverse movements, the one-space key being pivotally secured to the other and operating it through a partial stroke, and a stop for limiting the stroke of the one-space key, substantially as specified.
- 35 7. The combination with the paper-carriage

and the mechanism for reversing it, of two keys for imparting one-space and double-space reverse movements, the double-space key being connected to the reversing mechanism, and the single-space key being short and pivoted upon and operating the double-space key and having a stop limiting its stroke, substantially as specified.

8. The combination with the paper-carriage and the mechanism for reversing it, of two keys for imparting one-space and double-space reverse movements, the double-space key being connected to the reversing mechanism, and the single-space key being attached to the double-space key and operating said reversing mechanism through the latter, and a stop for limiting the stroke of the single-space key, substantially as specified.

9. The combination with the paper-carriage and its reversing mechanism of both a single-space reverse-key and a double-space key, operable independently at will, but connected together so that one operates the reversing mechanism through the other, substantially as specified.

10. The combination with the paper-carriage and its reversing mechanism, of a key for causing a double-space reverse movement connected to and operating said mechanism, and a key for causing a single-space reverse movement operating said mechanism through the first-mentioned key, substantially as specified.

11. The combination with the paper-carriage and its reversing mechanism, of a key for causing a double-space reverse movement connected to and operating said mechanism, and a key for causing a single-space reverse movement imparting a partial stroke to said first-mentioned key and thus operating said mechanism, substantially as specified.

12. The combination with the paper-carriage and its reversing mechanism, of a key for causing a double-space reverse movement connected to and operating said mechanism, and a key for causing a single-space reverse movement attached to and imparting a partial stroke to said first-mentioned key and thus operating said mechanism, substantially as specified.
